ATTORNEY

UNITED STATES PATENT OFFICE.

ARTHUR BRIGDEN, OF BIRMINGHAM, ALABAMA.

DISK HARROW AND CULTIVATOR.

1,292,697.

Specification of Letters Patent. Patented Jan. 28, 1919.

Application filed August 31, 1918. Serial No. 252,176.

To all whom it may concern:

Be it known that I, ARTHUR BRIGDEN, a citizen of the United States, residing at Birmingham, in the county of Jefferson and 5 State of Alabama, have invented a new and useful Disk Harrow and Cultivator, of which the following is a specification.

This invention has reference to disk harrows and cultivators, and its object is to provide a disk carrier whereby the angle of the 10 plane of the disk to the line of travel may be changed and the tip of the disk to the vertical may be changed to suit various conditions.

15 In accordance with the invention each disk is mounted on a stub shaft with which it may turn and the stub shaft is carried by a block, which latter is capable of swinging about an axis displaced to one side of the axis of rotation of the disk so that the disk is pendently supported, but the support may be clamped in different positions of adjustment. Furthermore, the block is mounted in a carrier also capable of adjustment about a 20 vertical axis so that the disk may be adjusted about either or both of two axes arranged at right angles one to the other, one being substantially vertical and the other substantially horizontal.

30 The invention will be best understood from a consideration of the following detailed description taken in connection with the accompanying drawing forming part of this specification, with the understanding, however, 35 that the invention is not confined to any strict conformity with the showing of the drawing but may be changed and modified so long as such changes and modifications mark no material departure from the salient 40 features of the invention as expressed in the appended claims.

In the drawing:

Figure 1 is a plan view of a cultivator or harrow embodying the invention.

45 Fig. 2 is a perspective view of the disk carrier.

Fig. 3 is a vertical section through the disk and carrier.

50 Fig. 4 is a section at right angles to that of Fig. 3.

Referring to the drawing, there is shown a disk harrow or cultivator 1 which, in general arrangement, may correspond to cultivators already in use and comprises a main 55 beam 2, laterally extended bars 3, 4, levers

5, 6, respectively, for adjusting the bars 3 and 4, and links 7 connecting the levers to the bars. Guide segments 8 serve to support the bars 3 and 4 from the beam 2. No attempt is made to particularly illustrate the 60 body of the cultivator or the operating parts, the invention being directed to the means for mounting the cultivator disks, which latter are indicated at 9 and may be of the usual dished disk type.

65 Each disk 9 is carried by a hub 10 having at one end a flange 11 against which the disk may seat and to which it is secured by rivets 12 or otherwise. Each disk is furthermore mounted on an axle 13 which may turn with 70 the disk, the hub 10 being held to the axle 13 by a countersunk set screw 14 located, in the particular showing of the drawing, on the concave side of the disk. The axle 13 extends beyond the flange 11 for a suitable 75 distance and terminates in a head 15.

75 There is also provided a block 16 which may be in the form of a casting bored to be traversed by the corresponding portion of the axle 13 and countersunk, as shown at 17, 80 to receive the head 15. The opposite end of the bore through the block 16 is countersunk, as shown at 18, to receive a washer 19 surrounding the axle adjacent to the flange 11. By this arrangement the axle or shaft 13 85 may turn in the block 16 but dust and dirt are excluded from the bearings of the shaft by the head 15 at one end and the washer 19 at the other end. An oil hole 20, indicated in Fig. 3, provides for lubricating the axle 90 where it turns within the block 16.

95 There is also provided a hanger 21 which may be in the form of a strap with legs 22 converging from a yoke or base portion 23 and terminating at the free ends, which are the lower ends, in substantially parallel extensions 24 embracing the block 16. The extensions 24 are traversed by bolts 25 and 26 respectively holding these extensions close to the block 16 and preventing the spread of 100 the legs of the hanger. The bolt 25 traverses the block 16 at a high point thereof above the axle 13 so that the block is pendently supported. At the lower end the block is provided with an arcuate recess 27 curved about the axis of the bolt 25 as a center and this recess has end walls in the form of flanges 28 in the path of which is located the bolt 26, the arrangement being such that the block may be swung about the bolt 25 to an 105 110

extent determined by the length of the recess 27 between the flanges 28, the axis of swinging being about the bolt 25.

The yoke portion 23 of the hanger 21 has 5 oppositely curved slots 29 therethrough on opposite sides of the upright central axis of the hanger. The slots 29 are traversed by bolts 30 in the bars 3 and 4.

The slots 29 permit individual adjustment 10 of the hangers 21 with relation to the bars 3 and 4 while the levers 5 and 6 permit mass adjustments of the disks, this last feature not entering into the present invention and hence requiring no particular mention. Be- 15 cause of the adjustability of the hangers the angle of the disks to the line of travel may be varied. By means of the pendent blocks 16 the tilt of the disks with relation to the surface being acted upon may be 20 varied so as to throw as much or as little dirt as desired. The disks may be used either side out by loosening the set screw slipping the disk with its hub off from the axle or shaft and then turn it over or re- 25 place it.

When the block 16 is tilted as desired, it is locked in the adjusted position by means of a set screw 31 carried by one of the legs 22 and bearing against one side of the block 30 16. The bolts 25 and 26 may be tightened to hold the block 16 but reliance need not be had upon this manner of fastening the block since the set screw 31 is more reliable.

What is claimed is:—

35 1. A mounting for the disks of disk har- rows or cultivators, comprising a hanger formed of a base portion with depending spaced legs, a block pivotally mounted be- 40 tween the legs of the hanger, a shaft or axle mounted in the block at right angles to the pivot of said block for carrying a disk, and means for limiting the pivotal movement of the block.

2. A mounting for the disks of disk har- 45 rows or cultivators, comprising a hanger formed of a base portion with depending spaced legs, a block pivotally mounted be- 50 tween the legs of the hanger, a shaft or axle mounted in the block at right angles to the pivot of said block for carrying a disk, said block being pendentally supported with respect to the longitudinal axis of the hanger, and means for limiting the pivotal move- 55 ment of the block and for fixing it in its adjustment.

3. A mounting for the disks of disk har- 60 rows or cultivators, comprising a hanger having means for the attachment of the hanger to supporting means, said hanger being provided with pendent legs, a block 65 located between the legs of the hanger, a pivotal support for the block from which the latter is pendentally hung, a stop member on the hanger below the block, the latter having a recess with end walls for engaging

the stop member at opposite ends of the pendent movement of the block, and an axle for carrying a disk, said axle being mounted in the block and participating in the movements of adjustment of said block.

4. A disk mounting for use in connection with disk harrows and cultivators, comprising a hanger with a yoke portion having slots for the attachment of the hanger to supporting means in different positions of adjustment with relation to the line of travel of the harrow or cultivator, said hanger having depending legs, a block lodged between the lower ends of the legs, pivot means extending between the legs and block for pendentally supporting the latter, stop means below the block, the latter having a recess with terminal walls into the path of which the stop means is interposed, an axle journaled in the block to one side 80 of the pivot support of the block, and a disk having a hub adapted to be applied to the shaft, said hub having a set screw for securing the hub and disk to the shaft for removal of the disk and replacing it in the re- 90 verse position at will.

5. A disk mounting for use in connection with disk harrows and cultivators, comprising a hanger with a yoke portion having slots for the attachment of the hanger to supporting means in different positions of adjustment with relation to the line of travel of the harrow or cultivator, said hanger having depending legs, a block 95 lodged between the lower ends of the legs, pivot means extending between the legs and block for pendentally supporting the latter, stop means below the block, the latter having a recess with terminal walls into the path of which the stop means is interposed, an axle journaled in the block to one side 100 of the pivot support of the block, and a disk having a hub adapted to be applied to the shaft, said hub having a set screw for securing the hub and disk to the shaft for removal of the disk and replacing it in the re- 110 verse position at will, the block having countersinks at opposite ends of the journal 115 bearings for the shaft for the reception of dust excluding means, and the hanger being provided with a set screw in position to engage the block to hold the latter in adjusted positions.

6. In combination with supporting means having a pair of spaced bolts with nuts, a 120 hanger having a base portion with oppo- 125 sitely curved slots on opposite sides of the upright central axis of the hanger, said slots being traversed by said bolts, a block pivotally mounted in said hanger on a horizontal pivot, and an axle journaled in the block at right angles to the pivot of said block, said axle carrying a disk.

7. In combination with supporting means having a pair of spaced bolts with nuts, a 130

hanger having a base portion with oppositely curved slots on opposite sides of the upright central axis of the hanger, said slots being traversed by said bolts, said hanger having spaced legs depending from said base portion, a block pivotally mounted between the legs of said hanger, an axle

journaled in the block at right angles to the pivot of said block, and a disk on said axle.

In testimony that I claim the foregoing 10 as my own, I have hereto affixed my signature.

ARTHUR BRIGDEN.
